UNITED STATES PATENT OFFICE

FREEMAN BAKER CUMMER, OF CARMAN, MANITOBA, CANADA

SIDING CLAMP

Application filed April 15, 1926, Serial No. 102,276, and in Canada April 24, 1925.

The invention relates to a siding clamp especially for carpenter's use in putting on siding and an object of the invention is to provide a tool which will draw siding boards together and hold them for nailing.

A further object of the invention is to construct the tool in a simple, cheap, efficient and durable manner so that it can be adjusted to accommodate various widths of siding.

With the above more important objects in view the invention consists essentially in the arrangement and construction of parts hereinafter more particularly described and later pointed out in the appended claims, reference being had to the drawing in which:

Fig. 1 is a perspective view of the clamp in working position.

Fig. 2 is a face view of the clamp.

Fig. 3 is a plan view of the clamp.
Fig. 4 is a vertical sectional view centrally through the clamp.

In the drawing like characters of reference indicate corresponding parts in the several figures.

The tool consists of an upper clamping jaw 1 and a lower anchoring jaw 2. The shank of the clamping jaw is provided with inturned marginal portions affording guides 3 and 4 between which the shank of the anchoring jaw 2 is slidably received. At their inner edges the guides 3 and 4 are provided with integral lug extensions 5 and 6 projecting outwardly at right angles thereto. The shank of the anchoring jaw 2 is provided with spaced longitudinally extending ribs 7 and 8 arranged to move freely between the guides 3 and 4. The ribs 7 and 8 are connected by bolt 9, link 10 and bolt 11 to the inner end of an operating lever 12 which is pivotally mounted between the lugs 5 and 6 through the medium of the pivot bolt 13. The pivoted end of the lever 12 is preferably bifurcated to provide a recess 14 for the reception of the attached end of the link 10. The point of connection between the ribs 7 and 8 and the link 10 may be varied by providing the ribs with a plurality of holes 15 in which the bolt 9 may be selectively engaged.

In explaining the operation of the tool, siding boards are generally made with a tongue

and grooves and ordinarily are quite easily put together. Quite often, however, due to various causes, such as warping of the boards, difficulty is experienced in getting them together as the warp makes a bulge at the centre. The tool will straighten out the warped board if used as follows:

The anchoring jaw is caught on the lower part of the last siding board that has been nailed. The extended clamping jaw is then placed over the tongue of the siding board next to be nailed. A downward pressure of the operating lever presses the siding board tightly into place where it can very easily be held while the operator nails it on.

The intense pressure developed between the jaws will obviously straighten out any warped board.

What I claim as my invention is:

1. A siding clamp comprising an anchoring jaw provided with a flat extending shank positioned at right angles to the jaw, a clamping jaw provided with a flat extending shank positioned at right angles to the clamping jaw and fitted with marginal guides slidably receiving the shank of the anchoring jaw, a pair of opposing spaced lugs carried by the guides, an operating lever pivotally carried by the lugs and a link pivotally connecting the lever to the shank of the anchoring jaw.

2. A siding clamp comprising an anchoring jaw and a flat shank extending at right angles to the jaw and provided at the side remote from the jaw with lengthwise extending, centrally located, reinforcing ribs, a clamping jaw opposing the anchoring jaw and provided with a flat extending shank fitted with marginal guides slidably receiving the edges of the shank of the anchoring jaw and having the guides extended to form a pair of opposing spaced lugs, an operating lever pivotally attached to the lugs and a link connected to the inner end of the lever and pivotally and adjustably attached to the ribs.

3. A siding clamp comprising a pair of jaws provided with flat shanks arranged in overlapping sliding engagement, spaced lugs carried by and extending at right angles to one of said shanks, spaced ribs carried by the other shank and provided with a plurality of

registering holes, a lever pivotally secured between said lugs, a link having one end extending between the lugs and pivotally secured to said lever and a bolt passing through the other end of the link and through selected 5 registering openings of the ribs.

Signed at Carman this 23rd day of March, 1926.

FREEMAN BAKER CUMMER.
